UNITED STATES PATENT OFFICE

DUDLEY D. LEVY, OF NEW YORK, N. Y., ASSIGNOR TO DUDLEY RESEARCH CORPORATION, OF NEW YORK, N. Y., A CORPORATION OF NEW YORK

LATCH FOR DUMB-WAITER DOORS

Application filed September 7, 1929. Serial No. 390,961.

This invention relates to a new and useful latch whereby the doors for dumb-waiter elevator shafts are locked when the dumb-waiter is out of receiving position, and are unlocked by the waiter when said waiter is in receiving position.

In houses that are equipped with dumb-waiter service it frequently happens that tenants or their servants open the door of the 10 dumb-waiter shaft and throw rubbish down the shaft without waiting for the waiter to be brought into receiving position. This action causes much trouble and results in great annoyance and it is the prime object of 15 my invention to provide a latch for doors of dumb-waiter shafts such that a door equipped with my latch cannot be opened to a sufficient extent for rubbish to be thrown down the shaft when the waiter is not in receiving 20 position.

Another object of my invention includes the provision of means whereby the shaft door may be opened to a small extent and still be kept in latched position. From this position 25 it is unlocked by the dumb-waiter when said waiter is brought into receiving position.

A further object includes the provision of an efficient and simple latch for dumb-waiter doors which may be readily applied and 30 which is thoroughly reliable and efficient in operation.

A still further object includes the provision of a pair of slidably mounted parallel bars having one end of each of said bars pivotally united to the respective door and door 35 sill, and means for unlatching said device by the action of the dumb-waiter being brought into receiving position.

Other objects will appear hereinafter and 40 I attain these objects by a construction illustrated in the accompanying drawings, in which

Figure 1 is a view of a door and door sill for a dumb-waiter shaft having my latch device applied thereto and showing the door in closed position;

Fig. 2 is a view similar to that of Fig. 1 but showing the door in open position with the dumb-waiter engaging the unlatching device;

Fig. 3 is a view taken on the line 3—3 of Fig. 2;

Fig. 4 is a view showing the relation of the unlatching device and the latch as applied to a door sill;

Fig. 5 is a view taken on the line 5—5 of Fig. 2 looking in the direction of the arrows;

Fig. 6 shows portions of the respective ends ⁵⁵ *a*, *b*, and relations of the door latch member and door sill latch member at their notched ⁶⁰ portions:

Fig. 7 is a view of a portion of a waiter shaft showing the dumb-waiter shaft door and waiter about to be brought into position for unlatching said door; and

Fig. 8 is a view at right angles to that of Fig. 7.

The same reference characters represent like parts throughout the several views ⁷⁰ wherever they appear.

Referring now to the drawings wherein there is shown a form of construction suitable for the purpose stated and by which I accomplish the objects of my invention. In said drawings a dumb-waiter door is represented at 10. This door is hingedly attached to the door frame 11 which is provided with a door sill 12 on the dumb-waiter shaft 13. In this shaft there operates in the usual manner the dumb-waiter 14. An unlatching device 15 is provided which extends into the path of said dumb-waiter and is operated by a strike-plate 16, on the dumb-waiter, when said waiter is brought into receiving position. ⁷⁵

The door 10 is normally held in closed position by spring hinges 17, of the usual construction, and latch 18 keeps the door fastened. On the inner side of said door at a suitable distance from the opening end ⁸⁰ thereof there is provided a pivoted anchor 19 on which is pivotally mounted the door latch member 20. On the door sill near the hinged side of the door there is provided a bracket 21 on which is pivotally mounted the door sill latch member 22. This member is held in position by suitable means such as a rivet or stud 23 engaging an elongated slot 24 in said door sill latch member. A spring 25 on stud 23 normally depresses the ⁸⁵ ⁹⁰ ⁹⁵ ¹⁰⁰

door sill latch member 22 so that the same will tend to assume a flat position on its companion door latch member 20 and in so doing will press on edge 41 of the latching device 5 15 so as to hold the same in the path of the dumb-waiter as is indicated by dotted lines in Fig. 3.

By referring to Fig. 2 it will be apparent that the door latch member 20 is provided 10 with a stop notch 26 near the pivotally mounted end thereof. This stop notch is so positioned that the stop pin or lug 27 near the free end of the door sill latch member 22 will engage and lock the door. 15 The free end of door latch member 20 is provided with a band or guide 28 which slidably engages the door sill latch member 22. Member 20 is also provided with a stop pin or lug 29 which is positioned to engage 20 an elongated stop notch 30 on the door sill latch member 22 near its pivoted end, thereby permitting the door to be locked in partially open position. The free end of the door sill latch member 22 likewise is provided with 25 a guide band 31 and a stop pin or lug 27 for the purpose stated above.

From this construction it will be apparent that I provide a pair of parallel bars which are slidably mounted with respect to their 30 free end but are pivotally mounted with respect to their secured ends. This construction affords very simple but efficient means for latching the door in locked and partially closed, or fully closed positions but 35 unlocking the same by the dumb-waiter when said dumb-waiter is brought into receiving position. The elongated slot 24 in the end of the door sill latch lever 22 further provides means for opening the door a little 40 more so that it is possible to use the elevator shaft as a means of communication with a neighbor above or below.

By referring to Fig. 3 it will be seen that the unlatching device 15 is mounted on 45 a bracket 21 by a pin or screw 40 and said unlatching device is provided with a beveled edge having an elongated nose or edge 41 to engage one side of the door sill latch member 22 thereby tilting said latch member suffi- 50 ciently to release the stop pins or lugs 27 and 29. This is accomplished by the dumb-waiter being brought into receiving position. Under this condition the door may be easily 55 opened and when the door is closed and the waiter brought out of receiving position said latch device becomes fully operative to lock the door as stated above.

It is obvious that various minor changes 60 may suggest themselves to those versed in the art which, however, will fall fully within the scope and spirit of my invention.

What I claim, therefore, as new and useful and desire to secure by Letters Patent is:

1. In a latch for dumb-waiter doors, the 65 combination of a pair of parallel bars mount-

ed for engaging each other at their opposite ends, guide members on said bars for holding the same in sliding engagement, means for pivotally supporting each of said bars at one end thereof, said bars each having a notch, and means on each of said bars for engaging said notch, said means disposed to lock the door before it is completely closed. 70

2. In a latch for dumb-waiter doors, the combination of parallel bars, one of said bars being pivotally mounted on the door of said dumb-waiter shaft and the other of said bars being pivotally mounted on a part of the door frame, said bars each having a notch near 75 its pivotally mounted portion, means for engaging each of said notches, and means for rocking one of said bars to disengage said notch engaging means. 80

3. A door latch device comprising bars 85 slidably mounted, said bars each having a notch in one edge thereof, a guide band and stop pin at one end of each of said bars, said pin engaging a notch on its companion bar, and an unlatching device engaging one of 90 said bars for tilting the same in unlatching the door. 95

4. In a latch for dumb-waiter doors, the combination of parallel bars slidably engaging each other at their opposite ends, means for pivotally supporting said bars at the 100 other ends thereof, means on each of said bars for limiting the slideable movement, means for tensioning one of said bars in locking position onto the other of said bars, and a pivotally mounted unlatching device extending into the path of the dumb-waiter for rocking said bar to unlatch the same. 105

In testimony whereof I have hereunto set my hand on this 3rd day of September, A. D. 1929.

DUDLEY D. LEVY.
